CAN BODY MAKING MACHINE

John H. Murch, East Orange, N. J., assignor to
 American Can Company, New York, N. Y., a
 corporation of New Jersey

Application August 24, 1940, Serial No. 354,114

6 Claims. (Cl. 93—36)

The present invention relates to can body making machines and has particular reference to shifting the body forming horn relative to other parts of the machine so that can bodies or can body blanks may be readily extricated from the machine when a jam of such bodies or blanks occur. This is an improvement on the can body maker disclosed in United States Patent 2,169,311, issued August 15, 1939, to M. E. Widell.

In the manufacture of can bodies made of sheet metal or fibre material, the body blanks are usually fed along a predetermined path of travel adjacent a stationary forming horn and are wrapped or folded around the horn to produce the finished can body. During this passage along the horn a blank or a partially made body occasionally is crushed and thus jams the feeding device. Such crushed can bodies are sometimes difficult to extricate from the machine.

The instant invention contemplates overcoming this difficulty by providing a movable forming horn which may be raised out of the way so that sufficient clearance obtains between the horn and the feeding devices to readily extricate a crushed or jammed blank or body.

An object therefore of the invention is the provision of a can body making machine wherein the forming horn is movable relative to the feeding devices so that it may be shifted relative to the other parts of the machine to facilitate extrication of can bodies or can body blanks which have been crushed when a jam of such bodies or blanks occurs in the machine.

Another object is the provision of such a machine wherein the forming horn may be raised bodily while maintaining it parallel with the feeding devices in the machine.

Another object is the provision in a machine of this character of devices for locking the forming horn in a desired position so that it may be maintained stationary after being shifted to extricate a crushed body or blank.

Numerous other objects and advantages of the invention will be apparent as it is better understood from the following description, which, taken in connection with the accompanying drawings, discloses a preferred embodiment thereof.

Referring to the drawings:

Figure 1 is a side elevation of a can body making machine embodying the instant invention, with parts broken away and parts shown in section;

Fig. 2 is an enlarged vertical section taken substantially along the line 2—2 in Fig. 1, with parts broken away; and

Fig. 3 is a sectional view taken substantially along the line 3—3 in Fig. 2.

As a preferred embodiment of the instant invention the drawings illustrate a can body mak-

ing machine of the character disclosed in the above mentioned Widell patent.

In such a machine flat can body blanks of fibre material are supported in a horizontal position on top of a bed 11 (Figs. 1 and 2) which constitutes the main frame of the machine and are advanced therealong in a step by step movement through a series of working stations by feeding devices. These devices include a pair of spaced and parallel feed bars 12 carrying feed dogs 13 which engage behind the blanks during their advancement. These feed bars operate in grooves 14 formed in the top of the bed 11.

As the blanks are advanced along the bed 11 they are wrapped or folded around a horn 16 which is disposed just above the top of the bed in spaced relation thereto and which extends longitudinally thereof. The drawings show a square horn so that the folded blanks will result in can bodies A of square cross section. Longitudinal grooves 17 formed in the bottom of the horn provide clearance spaces in which the feed dogs 13 operate.

The horn 16 is suspended from above in order to maintain it in spaced relation to the bed 11 and also to permit wrapping of the blank around the horn. For this purpose there are two lugs or brackets 21 (Figs. 2 and 3) bolted to the top of the horn in spaced relation and adjacent the inner end of the horn so that its outer end may be free and unobstructed.

The lugs 21 extend upwardly alongside of vertical face plates 22 (Fig. 2) which are formed on overhanging arms 23 of a pair of spaced brackets or horn supports 24 (see Fig. 1) bolted to the bed 11. The upper ends of the lugs are fastened to the face plates by eccentric bolts or pins 27. These pins include a body 31 having on one end thereof an eccentric portion 32 which terminates in an enlarged head 33 and having on the opposite end a shouldered portion 34 of reduced diameter which terminates in a threaded section 35.

The body 31 of each bolt 27 is located in a bore 37 formed in the face plate 22 of each bracket 24. The eccentric portion 32 of the bolt is disposed in a hole 38 formed in each lug 21 while the enlarged head seats within a clearance recess 39 formed in the lugs. The shouldered portion 34 of the bolts carry lever arms 42 (see also Fig. 1) to which they are keyed and these lever arms are connected in parallelism by a horizontal link 43. One of the lever arms extends upwardly to form a handle 44. The threaded section 35 of each bolt carries a locknut 46 having a turning or operating handle 47.

Hence with the horn 16 in operating position closely adjacent the bed 11 and feed bars 12, as best shown in Fig. 2, the locknuts 46 are turned up tight against the lever arms 42 and this draws

the enlarged head 33 of each bolt or pin 27 tight against the horn lugs 21. Such tightening of the bolts clamps the lugs against the face plates 22 and thus locks the horn and the lever arms 42 against displacement.

When a jam of body blanks or partially made can bodies occurs in the machine and it is desired to raise the horn so that the crushed can parts may be extricated, it is merely necessary to unclamp the horn lugs by turning the lock-nuts 46 in a reverse direction and then to shift the lever handle 44 toward the right as viewed in Fig. 1. Unclamping the locknuts frees the lever arms 42. Shifting of the lever handle 44 rotates the body portions 31 of the pins 27 in their bores 37 and this revolves the eccentric portions 32 of the pins in their holes 38 of the horn lugs. Such movement lifts both of the lugs and the horn connected therewith while maintaining the horn in parallelism with the machine bed 11 so that a greater space obtains between the bottom of the horn and the top of the bed. It is this greater space that permits ready removal of the crushed can parts.

After removing the jam the horn may be quickly returned to its operating position by a reverse shifting of the lever handle 44 to its original position, as shown in Figs. 1 and 2. The pins are then drawn up tight by manipulation of the locknuts 46 and this again clamps the lugs 21 against the face plates 22 so that the horn and the lever handle will be locked against movement during the operation of the machine.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a can body making machine, the combination of feeding devices for advancing fibre can body blanks along a predetermined path of travel, a forming horn disposed adjacent the path of travel of the blanks and around which the blanks are wrapped to produce can bodies, devices for supporting said horn spaced from the path of travel of said feeding devices, and means carried by said supporting devices and engageable with said horn for shifting the same relative to said feeding devices so that crushed fibre body blanks may be readily extricated when a jam occurs in the machine between said horn and said feeding devices.

2. In a fibre can body making machine, the combination of feeding devices for advancing can body blanks along a predetermined path of travel, a forming horn disposed adjacent the path of travel of the blanks and around which the blanks are wrapped to produce can bodies, devices for supporting said horn spaced from the path of travel of said feeding devices, means carried by said supporting devices and engageable with said horn for bodily shifting the same relative to said feeding devices so that crushed body blanks may be readily extricated when a jam occurs in the machine between said horn and said feeding devices, and instrumentalities for locking said horn against movement in its shifted position.

3. In a fibre can body making machine, the

combination of feeding devices for advancing can body blanks along a predetermined path of travel, a forming horn disposed adjacent the path of travel of the blanks and around which the blanks are wrapped to produce can bodies, stationary devices for supporting said horn at places intermediate its ends and spaced from the path of travel of said feeding devices, and parallel lever means carried by the supporting devices and connecting with said horn for raising it further away from said feeding devices while maintaining it in parallelism therewith so that crushed body blanks may be readily extricated when a jam occurs in the machine.

4. In a fibre can body making machine, the combination of feeding devices for advancing can body blanks along a predetermined path of travel, a forming horn disposed adjacent the path of travel of the blanks and around which the blanks are wrapped to produce can bodies, a stationary bracket member disposed adjacent said horn for supporting the same spaced from the path of travel of said feeding devices, a lug member on said horn and engaging against said bracket member, a connecting pin extending through said members and having an eccentric portion disposed in one of said members, and means for rotating said pin to move the horn further away from the feeding devices so that crushed body blanks may be readily extricated when a jam occurs in the machine.

5. In a can body making member, the combination of feeding devices for advancing fibre can body blanks along a predetermined path of travel, a forming horn disposed adjacent the path of travel of the blanks and around which the blanks are wrapped to produce can bodies, a stationary bracket member disposed adjacent said horn for supporting the same in spaced relation above the path of travel of said feeding devices, a lug member on said horn and engaging against said bracket member, connecting pins extending through said members each having an eccentric portion disposed in one of said members, means for rotating said pins to elevate the horn still further away from the feeding devices so that crushed body blanks may be readily extricated when a jam occurs in the machine, and a locknut carried on each of said pins for locking it against movement to hold said horn stationary and in a desired operative or inoperative position.

6. In a fibre can body making machine, the combination of feeding devices for advancing can body blanks along a predetermined path of travel, a forming horn disposed adjacent the path of travel of the blanks and around which the blanks are wrapped to produce can bodies, a plurality of stationary brackets disposed adjacent said horn for supporting the same in spaced relation relative to the path of travel of said feeding devices, a plurality of lugs formed on said horn and engaging against said brackets, rotatable pins carried in said brackets and lugs for holding them together, each of said pins having an eccentric portion disposed in a said horn lug, a lever secured to each pin, and a link connecting the levers in parallelism so that the shifting of one lever will shift all levers and rotate all pins in unison to move the horn relative to the feeding devices and in further spaced relation thereto so that crushed body blanks may be readily extricated when a jam occurs in the machine.

JOHN H. MURCH.
